PRODUCTION OF VALUABLE ORGANIC PRODUCTS

Mathias Pier, Heidelberg, Karl Winkler and Kurt Wissel, Ludwigshafen-on-the-Rhine, Germany, assignors, by mesne assignments, to Standard-I. G. Company, Linden, N. J., a corporation of Delaware

Application May 25, 1928, Serial No. 280,642
In Germany May 28, 1927

9 Claims. (Cl. 196—53)

This invention relates to the production of valuable organic products, in particular liquid hydrocarbons, by the treatment of distillable solid carbonaceous substances, especially coal or substances of the nature of coal including peat, wood, brown-coal and the like at an elevated temperature.

We have found that in the production of valuable organic products by heat treatment of the said carbonaceous materials, if desired with application of pressure, and together with or in the absence of inert or hydrogenating gases, with or without an addition of solvents and with or without the employment of catalysts, namely in destructive hydrogenation or destructive distillation, it is very advantageous to first subject the said initial materials to a preliminary treatment which breaks up and loosens the material, in a manner disrupting the capillary skeleton of the initial material, thus rendering the material more suitable for the further treatment and in particular liberating the vaporous or liquid constituents contained therein or such as are capable of being liquefied at an elevated temperature, or at least rendering these readily accessible to the further treatment. In this way the decomposition of the carbonaceous material in the further treatment is greatly facilitated and the yield of valuable liquid products is greatly increased.

30 The said preliminary treatment consists in a treatment under pressure usually without an addition of liquid organic solvents, at a temperature which is higher than that employed in the ordinary briquetting processes, that is to say usually above 100° C. but should be substantially below the coking point of the carbonaceous material. Thus the said treatment may be carried out at temperatures of between 200 and 450° but preferably between 300° and 400° C.

40 The preliminary treatment may consist for example in heating the initial materials i. e. the distillable solid carbonaceous substance referred to above in a closed apparatus in the absence of an added solvent so that they are exposed to the pressure of their own vapors.

The materials may also be subjected to mechanical pressing in a heated condition, the temperature employed being, however, higher than in ordinary briquetting, or the pressure may be produced by admitting gases substantially free from hydrogen, such as nitrogen, carbon dioxide, water vapor and the like. The degree of pressure and the duration of the treatment depends on the products to be treated and on the nature

of the process in the further treatment, which, in turn, is modified to suit the products desired. Pressures of 50, 100, 200 or even 1000 atmospheres and more are employed.

The initial materials to be subjected to the preliminary treatment may be employed in the form of aqueous pastes which may be free-flowing or rather thick in consistency. The said initial material may also however be treated in the presence of or suspended in other non-solvents for the liquid products obtained, for example molten or liquid metals, such as lead, tin, bismuth, mercury and alloys of low melting point hereinafter referred to as "metals liquid at the reaction temperature".

In certain circumstances it is advisable to add other substances, which may be solids, liquids or gases substantially free from hydrogen, during the preliminary treatment under pressure, since, by such means, the subsequent decomposition of the carbonaceous substances can be considerably increased and accelerated. Particularly suitable for this purpose are substances with an alkaline reaction, such as oxides, hydroxides and carbonates of alkali or alkaline earth metals or sulfids containing strongly basic constituents, like the sulfids of the alkali metals and alkaline earth metals, but other substances either inert or exhibiting catalytic properties, may also be employed, such as iodine or other metalloids.

The initial materials which have undergone the said preliminary treatment are then subjected either partially or in their entirety to a heat-treatment proper for the production of valuable products, in particular of liquid hydrocarbons, from carbonaceous materials as aforesaid. For example the liquid constituents may be separated from the solid constituents and the two portions be treated separately.

In the preliminary treatment injurious substances, such as free iron, nickel, and the like capable under the specified conditions of giving rise to secondary reactions such as the formation of coke and undesirable gases should preferably be excluded.

The nature of the present invention will be further explained with reference to the accompanying drawing diagrammatically showing a plant in which the process according to this invention may be carried out with advantage.

Referring to this drawing in detail numeral 3 denotes a stirring vessel provided with a stirrer 3a. Into this vessel comminuted coal is introduced at 1, while an aqueous solution of sodium sulphide is supplied at 2. The coal is pasted up with the

said solution of sodium sulphide and then, by means of pump 4, conveyed into the preheating coil 5, from whence it is passed into the high pressure vessel 6. In this high pressure vessel 5 the preliminary treatment, which breaks up and loosens the material in a manner disrupting the capillary skeleton thereof, takes place. The materials issuing from the said high pressure vessel are then led into the cooler 7 and from thence, 10 by way of pressure release valve 8, into a centrifuge in which the liquid parts are separated from the solid constituents. The solid constituents are removed at 10. The liquid constituents pass through the perforated side wall of the centrifuge and are then pumped by means of pump 11 into the preheating coil 14, whereupon they pass into the high pressure vessel 15 in which they are subjected to destructive hydrogenation by means of hydrogen supplied at 13 and likewise preheated in the preheating coil 14. The products having undergone destructive hydrogenation are cooled in cooler 16 and then passed into vessel 17 from which the liquid portions of the said products may be withdrawn at 19 while the uncondensed gases escape at 18.

The following example further illustrates the nature of this invention which however is not restricted thereto.

Example

30 Brown-coal is made into a paste with water and 5 to 10 per cent of sodium sulfid, and forced at 200 atmospheres and at about 360° centigrade, by means of a pump, through a high pressure apparatus the interior of which is constructed of a steel containing a high percentage of chromium and nickel, the pressure being then released after cooling. By this means, up to 50 per cent of the coal substance is liquefied, practically without any production of gas.

40 The liquid constituents of the reaction product are then separated from the solids, and the former are again pumped through a high-pressure apparatus, in which they are treated, at 200 atmospheres and at a temperature from 440° to 450° centigrade with hydrogen in the presence of a molybdenum-chromium catalyst.

45 The effluent products from this treatment contain about 25 per cent of benzine, the remainder 50 consisting of hydrocarbon products boiling up to 350° centigrade.

What we claim is:—

55 1. A process for the production of valuable liquid organic products, in particular liquid hydrocarbons, by the destructive hydrogenation of dis-

tillable solid carbonaceous materials, which comprises subjecting said materials to a preliminary heat treatment at a temperature above 100° C., but below the coking point of said carbonaceous materials and under a pressure of at least 50 atmospheres, while excluding added organic solvents and gases containing a substantial amount of hydrogen to thereby disrupt the capillary skeleton of said materials and liquefy a large portion thereof, separating the resulting liquids from the solids and separately destructively hydrogenating said separated liquid and solid products.

2. The process as defined in claim 1 wherein the preliminary heat treatment is effected in the presence of a substance having an alkaline re- 90

95 3. The process as defined in claim 1 wherein the preliminary heat treatment is carried out in the presence of a sulphide of a strongly basic metal.

4. The process as defined in claim 1 wherein the preliminary heat treatment is effected in the presence of water.

5. The process as defined in claim 1 wherein the distillable carbonaceous material is brown 100 coal.

6. The process as defined in claim 1 wherein the preliminary heat treatment is carried out in the presence of a metal, liquid at the temperature employed in said heat treatment and 105 selected from the class consisting of lead, tin, bismuth, mercury and alloys containing one of said metals.

7. The process as defined in claim 1 wherein the liquids produced in the preliminary heat 110 treatment are separately subjected to destructive hydrogenation.

8. The process as defined in claim 1 wherein the solids obtained in the preliminary heat treatment are separately subjected to destructive hy- 115 drogenation.

9. The destructive hydrogenation of brown-coal, which comprises making brown coal into a paste with water and subjecting it to a preliminary treatment in the presence of an alkali 120 metal sulfid at about 360° C. to a pressure of 200 atmospheres, thereupon separating the liquid products obtained and then subjecting these to a treatment with hydrogen at a pressure of 200 atmospheres and at a temperature of about 125 440 to 450° C. in the presence of a molybdenum chromium catalyst.
